STAPLE PULLING MACHINE

Charles A. Robinson, Salem, Mass., assignor to
 United Shoe Machinery Corporation, Paterson,
 N. J., a corporation of New Jersey

Application June 9, 1932, Serial No. 616,165

11 Claims. (Cl. 12—16)

This invention relates to machines for pulling fastenings and is herein illustrated as embodied in a machine for pulling staple fastenings from shoes, it being understood, however, that the invention is not limited to such use but is adaptable to other uses such as, for example, the pulling of tacks from shoes.

In the manufacture of certain types of shoes use is made of fastenings, such as staples, for the purpose of temporarily securing together the upper and insole while the cement, which forms the means for permanent attachment, is setting. In some instances such staples are later pulled out by hand or by machine, heretofore a comparatively slow process. This results from the fact that considerable care must be taken to locate each staple relatively to the pulling tool so that during its operation the tool will not engage the legs of the staple in such a way as to bend it, thereby making it difficult to withdraw without causing injury to the shoe, but will advance beneath the cross bar of the staple in position to pull it.

It is an object of the present invention to provide an improved fastening pulling machine which will be adapted to the pulling of fastenings such as staple fastenings which have been driven into a shoe temporarily to secure together the upper and insole. To this end, and as illustrated the invention provides a fastening pulling machine comprising a normally inoperative pulling member relatively to which a fastening in the work can readily be located in position to be pulled, together with means for rendering the tool operative to pull the fastening upon presentation of the work to the tool. Preferably, and as shown, the tool is pivotally mounted upon the frame of the machine and is arranged for movement heightwise thereof when the tool is engaged by the work, there being a continuously oscillated member adapted to engage an abutment upon the tool to cause oscillation of the tool in pulling a fastening from the work.

The construction above outlined is advantageous in that the work, such as a shoe, can be located relatively to the tool with the latter in effective position for pulling a fastening, such as a staple, while the tool is at rest, thus expediting the pulling operation and eliminating any likelihood of injury to the shoe by the tool while it is in motion.

Other objects and features of the invention will be apparent from the following detailed description when taken in connection with the

accompanying drawing and will be pointed out in the claims.

In the drawing,

Fig. 1 is a side elevation of a fastening pulling machine illustrating one embodiment of the invention;

Fig. 2 is a detail view partly in section of the fastening pulling mechanism; and

Fig. 3 is a perspective view showing the forward portion of the machine with the pulling tool in operative engagement with the work.

As shown in the drawing, the invention is illustrated as embodied in a machine for pulling staple fastenings such as staples 10 driven through the upper 12 and into the insole 14 of a shoe such as shoe 16, the pulling operation being performed by a pulling tool 18 pivotally mounted in the frame 20 of the machine and arranged to be oscillated by a driver bar 22.

The tool 18 comprises an elongated shank 24 having at its lower end a curved work-engaging portion 26. Extending from the forward side of the shank 24 is a projection 28 in the form of a wedge-shaped claw or tooth the under surface of which constitutes a continuation of the surface 26. The projection 28 is of such dimensions that it can be inserted readily between the legs and beneath the cross bar of staples to be pulled which ordinarily extend slightly above the surface of the upper of the shoe.

The tool 18 is carried by a slide 30 secured to the frame 20 by a bolt 32 passing through an elongated slot 34 in the slide and so arranged that the slide can be secured in various positions heightwise of the frame and driver bar 22. The slide is provided with a slot 36 within which the tool 18 is mounted upon a pin 38 which extends through an elongated opening 40 in the upper portion of the shank 24. The tool 18 is normally forced downwardly so that the pin 38 is in engagement with the upper portion of the wall of the opening 40, this being accomplished by a spring 41 connecting the upper end of the shank 24 to a pin 42 carried by ears 43 of the slide 30. This arrangement permits

upward movement of the tool under pressure of work forced upwardly against the surface 26 with the result that the pin 38 engages the lower wall of the opening 40 and the tool can be oscillated about the axis of the pin. The central portion of the shank 24 of the tool is cut away to form a recess 44 to provide clearance for the driver bar 22 when the tool is in its lowermost position. Below the cut-away portion 44 is a shoulder or abutment 46 which is adapted

to be engaged by the end of the bar 22 when the tool is in elevated position.

The slide 30 has an opening 48 to provide for the entrance of the driver bar 22. Below the opening 48 is a downwardly projecting portion 50 which serves as a gage against which a shoe, such as shoe 16, can be positioned to locate the shoe in a lateral direction with a row of staples therein in operative position relatively to the pulling tool 18. The slide is also provided with shoulders 52 above the gage portion 50 and extending forwardly therefrom, providing stops for limiting upward movement of the shoe as it is presented to the tool.

15 The driver bar 22 is arranged to be oscillated continuously by an eccentric 54 mounted upon shaft 56 and arranged to be driven by suitable means such as pulley 58.

In the operation of the machine, the pulling tool 18 is normally held in its lowermost or inoperative position in which position the driver bar 22 does not engage it, with the result that the tool is stationary. A shoe is presented to the tool bottom up with the side of the shoe in contact with the gage 50 and a staple therein located in alignment with the tool. The shoe is then forced upwardly toward the shoulders 52 and into engagement with the curved surface 26 of the tool 18 which is shifted heightwise upon its pivot pin 38 with the result that the shoulder 46 is brought into alignment with the driver bar 22 and upon the next forward movement of the bar the tool will be swung forwardly about the axis of the pin 38, with the result that the claw 28 will be swung beneath the cross bar of the staple, such as staple 10 as illustrated in Fig. 2, and will pull the staple from the shoe. It is to be noted that the curved surface 26 of the tool limits upward movement of the shoe bottom during the pulling movement, while the claw 28 is oscillated away from the shoe to pull the staple. When the shoe is disengaged from the tool the spring 38 will lower the tool to render it temporarily inoperative and the shoe can then be positioned with another staple in alignment with the claw and the operation repeated.

Having described the invention, what I claim as new and desire to secure by Letters Patent of the United States is:—

50 1. A fastening pulling machine, comprising a frame, a pulling tool mounted on the frame for pivotal movement and for movement heightwise of the frame, and a movable member operable upon heightwise movement of the tool to cause oscillation of the tool for pulling a fastening from work presented to the tool.

2. A fastening pulling machine, comprising a frame, a tool carried by the frame and mounted for oscillation relatively to the frame and movable bodily relatively to the frame, and a driving member operable upon bodily movement of the tool for causing oscillation of the tool to effect the pulling of a fastening from work presented to the tool.

65 3. A fastening pulling machine, comprising a frame, a driving member, a pivot carried by the frame, a fastening pulling tool loosely mounted upon the pivot, and an abutment upon the tool movable therewith into position to be engaged by the driving member upon forcing work against the tool.

4. A fastening pulling machine, comprising a

frame, a continuously operated driving member a pivot carried by the frame, and a fastening pulling tool loosely mounted upon the pivot and having an abutment movable with the tool into operative engagement with the driving member 80 to cause oscillation of the tool.

5. A machine for pulling staple-fastenings from shoes, comprising a frame, an oscillatory staple-fastening pulling tool mounted for movement heightwise of the frame, and a driving member operable upon forcing a shoe against the tool for causing oscillation of the tool to pull a staple-fastening from the shoe. 85

6. A machine for pulling staple-fastenings from shoes, comprising a frame, a continuously operated driving means, a staple-fastening pulling tool, means for mounting the pulling tool on the frame for movement heightwise thereof, means operable upon forcing the work in a direction heightwise of the frame against the tool to cause operative engagement of the tool and driving means, and means normally operable to maintain the tool in inoperative position relatively to the driving means. 90

7. A fastening pulling machine, comprising a frame, a pulling tool pivotally carried by the frame, continuously operated means for engaging the pulling tool to cause it to oscillate, means normally operative to hold the tool out of engagement with the continuously operated means, 95 and a gage for locating the work relatively to the tool when the latter is in inoperative position.

8. A fastening pulling machine, comprising a frame, a pulling tool pivotally mounted upon the frame for movement heightwise thereof, means for oscillating the pulling tool comprising a continuously operated member, an abutment upon the tool forming an operative connection between the tool and the continuously operated member, 110 and means for rendering the tool normally inoperative.

9. A fastening pulling machine, comprising a frame, a pin carried by the frame, a pulling tool loosely mounted upon the pin for movement 120 heightwise of the frame, the tool having a recessed portion and an abutment adjacent thereto, a driving member operable to engage the abutment to oscillate the tool, and means normally operative to position the tool with the recessed portion thereof in alignment with the driving member. 125

10. A fastening pulling machine, comprising a frame member having a shoe engaging shoulder, a pin carried by the frame member, a fastener 130 pulling tool loosely mounted upon the pin and having an end portion normally projecting beyond the shoulder, a driving member for oscillating the tool, and means operated upon presentation of a shoe against the shoulder in position 135 to engage the end portion of the tool for causing the driving member to engage the tool.

11. A fastening pulling machine, comprising a frame, a tool pivotally mounted in the frame and having a shank terminating in a work engaging portion and a claw integral with the shank and projecting therefrom adjacent to said portion, and means for oscillating the claw in response to pressure exerted by the work upon said working engaging portion. 140
